HOOD LATCH UNIT

Robert L. Townsend, Sherman Oaks, Calif., assignor to
A. S. Stearns Co.

Filed Oct. 30, 1969, Ser. No. 19,854

Term of patent 14 years

Int. Cl. D8—04

U.S. Cl. D8—265

FIG. 1 is a perspective view of a hood latch unit showing my new design, the spring being omitted for convenience of illustration;

FIG. 2 is a perspective view of the attaching bracket portion thereof;

FIG. 3 is a left side elevational view of the present invention;

FIG. 4 is a front elevational view of the present invention illustrated in closed position; and

FIG. 5 is a top view of the present invention.

The vehicle hood shown in broken lines is included for illustrative purposes only.

I claim:

The ornamental design for a hood latch unit, substantially as shown and described.
